COMBINED WINE BUCKET AND STAND

Harold Bloomfield, Chicago, Ill., assignor to Bloomfield
Industries, Inc., Chicago, Ill., a corporation of Illinois

Filed Aug. 2, 1960, Ser. No. 61,603

Term of patent 14 years

(Cl. D67—4)

Fig. 1 is a view in perspective of a combined wine bucket and stand showing my new design;

Fig. 2 is a side elevational view thereof;

Fig. 3 is a top plan view thereof; and

Fig. 4 is a top plan view of the stand with the bucket removed.

I claim:

The ornamental design for a combined wine bucket and stand, as shown and described.
